UNITED STATES PATENT OFFICE.

LEWIS L. SCOTT, OF ST. LOUIS, MISSOURI, ASSIGNOR TO ELECTROL INC. OF MISSOURI, OF ST. LOUIS, MISSOURI, A CORPORATION OF MISSOURI.

OIL-BURNING SYSTEM.

Application filed May 31, 1924. Serial No. 717,190.

This invention relates to an improved oil burning system and various novel constructions of parts involved in said system, and has special reference to improvements in 5 that type of oil burning system described and illustrated in my pending application Ser. No. 538,559, filed February 23rd, 1922.

One of the objects of the invention is to provide an improved flame director for directing the flame into the furnace.

Another object is to provide a novel construction at the entrance end of this flame director to promote intimate mixing between the air and fuel and to promote complete 15 combustion of the fuel.

Another object of the invention is the provision of an improved safety device comprising a float adapted to be operated by oil received from the flame director, if combustion fails to occur, the rise of the float acting to break the electric contacts in the motor circuit which operates the fuel pump and the fan.

Another object of the invention relates to 25 improved means for draining the fuel from the chamber containing the float, and simultaneously raising the float to render the motor inoperative until the draining mechanism has been returned to normal position.

Other objects of the invention relate to 30 details of construction and to combinations and arrangements of parts hereinafter described and particularly pointed out in the claims.

My invention is illustrated in the accompanying drawing in which—

Figure 1 is a view in front elevation of the burner proper;

Figure 2 is a view partly in side elevation 40 and partly in section thereof;

Figure 3 is a top plan view of the float chamber;

Figure 4 is a transverse sectional view 45 thereof showing its connection with the air or mixing chamber of the burner; and

Figure 5 is a diagrammatic view designed 50 to illustrate the electrical control system employed and the manner in which the safety device operates to break the circuit to the motor in a system such as I employ.

Referring now to the drawings and particularly to Figures 1 and 2, the numeral 1 indicates a motor which operates a fan or blower 2 mounted in a fan casing 3, the latter having a spout 4 leading to an air

chamber 5. The shaft 6 of the motor also operates a fuel pump 7 which is designed to deliver fuel through a pipe 8 to a spray nozzle 9. Entering the air chamber 5 from the side opposite to that containing the fuel nozzle 9, is a flame director 10, hereinafter described, and suitably mounted on the lower side of the casting containing the air chamber 5 is a float chamber 11 embodying the safety device of the invention. All these 65 parts are suitably connected to be supported upon legs or standards 12 which may be secured at their lower ends to the floor of the furnace room.

Referring now to the flame director shown 70 in Figure 2, the same comprises a relatively large pipe which is characterized by having a pronounced upward curve and, as shown, its outlet end is inserted in the ash door 13 of the furnace instead of in the fire door 14 75 as in my prior application referred to. The inner end 15 of this pipe is formed slightly converging or funnel-shaped and projects into the air chamber 5 through an opening in the front wall of the casting 16 enclosing 80 said chamber, and the pipe as a whole is secured to the wall of said casting by means of flanges 17 bolted to flanges 18 provided on the said casting. Extending inwardly from the inner end of the end 15 of pipe 10 is a 85 conical projection 19, the converging wall of which provides a circular space 20 between itself and the wall of the end 15. To permit of the escape of unburned fuel, as herein-after explained, I drill through the wall of 90 the end 15 on the under side thereof, a small hole 21 which, as shown, is located above the lowest level of the tube 10. Associated with the inner end of the flame director 10 and mounted in the front wall 22 of chamber 95 5 is the spray nozzle 9 previously referred to, and a spark plug 23. Mounted on the wall 22 within the air chamber 5 is a flat plate 24, shown also in dotted lines in Figure 1, the purpose of which is to direct the air entering chamber 5 from the blower 2 through conduit 4 around the spark plug with such force as to prevent combustion being maintained in the immediate zone of the spark plug, and thus prevent fouling thereof, and 100 also to promote the intimate mixture of the fuel and air.

Assuming fuel to be sprayed through the nozzle 9 and to be ignited by the spark plug 23, the air entering the chamber 5, passing 110

from the region of the spray nozzle, will enter the converging inlet 19 of pipe 10 which, as will be seen, forms a restricted orifice and thus promotes intimate mixing between the air and the fuel. Passing out of the inner end of the projection 19, the mixed air and fuel tend to expand and at the same time, the draft or movement of the mixture tends to produce a partial vacuum in the circular space 20 with the result that eddy currents are set up in this region, which, I find, has a very pronounced effect in promoting complete combustion of the mixture.

The end 15 could, if preferred, be made 15 separate from the tube 10 but I prefer to make it integral therewith and thus avoid a joint which would have to be packed to prevent leakage of the fuel.

With the construction described, if the fuel should fail to ignite, the major portion of the fuel spray is thrown against the walls of the flame director by the air from the blower and will run backward due to the upward curve of pipe 10 and through the small hole 21 into the bottom of chamber 5. Referring to Figure 4, I mount in the bottom wall of chamber 5, a short tube 25, the upper end of which projects slightly above the floor of the chamber. The object of having the hole 21 located above the lowest level of the pipe 10 and of having the end of the tube 25 project slightly above the floor of chamber 5 is to prevent small quantities of fuel which may be deposited in the bottom of tube 10 on initially starting the apparatus, from flowing into the chamber 5 and from said chamber into the float chamber to be subsequently referred to, and through repeated accumulations operating the safety cut-off device when it would be unnecessary to do so. Under the arrangement described, any small amount of oil accumulating in the bottom of pipe 10 would be ignited or vaporized by the heat of combustion and the same would occur as to any small amount of oil accumulating in the bottom of chamber 5.

I will now describe the safety cut-off device above referred to and the means for draining the same, referring particularly to Figure 4. Secured on the bottom of casting 16, containing the chamber 5, is a casting 26 which is provided with a bore 27, which at one end receives the end of the tube 25 above referred to, and at its other end communicates with a chamber 28 provided in a cylindrical casting 29, which is integral with the casting 26 (see also Figure 3). Mounted in the chamber 28 is a float 30 which is provided on its upper side with a stem 31, which is slidably mounted and guided in a bearing 32 secured in the top or cover 33 of chamber 28. Mounted in the cover 33 is a contact screw 34 having at its upper end a contact 35, and having a conductor 36 connected with its lower end. Mounted in the cover 33

is also a second contact screw 37 having a conductor 38 connected to its lower end. Connected at one end to the contact screw 37 is a curved spring metal contact arm 39 which is in normal engagement with the contact 35 and is provided at its outer end and on its underside with an insulating block 40 to be engaged by the upper end of stem 31 when the float rises, to lift the arm 39 out of engagement with the contact 35 and thus break the circuit to the motor, as hereinafter described. The parts just described are normally covered by a cap 41 pivotally mounted at 42 on the wall of casting 29 and yieldably held closed by means of a spring 80 arm 43.

Assuming the device to have been placed in operation and ignition not to have occurred, the fuel, as before stated, will flow backward in the pipe 10 and out through opening 21 into the air chamber 5, thence through tube 25 and bore 27 into chamber 28, causing the float 30 to rise and its stem to lift the arm 39. Assuming, further, that the cause which had prevented ignition has been remedied, it will next be necessary to drain the oil from chamber 28. The construction for effecting this will now be described, referring particularly to Figures 1, 3 and 4.

Rotatably mounted in a stuffing box 44 provided in the wall of the casting 29 is a tube 45 which is curved to provide an upward extension 46, the end of which is covered with a dust cap 47. Beyond the wall 100 of the casting 29, the tube 45 is cut away on one side to provide a semi-cylindrical extension 48, which is located in a recess 49 provided in the bottom of chamber 28, with its upper flat edges 50 lying flush with the floor 51 of said chamber. The end of the extension 48 abuts against the rear end 52 of the recess 49, and I insert through an opening in the extension 48 adjacent to the side of the wall of casting 29, through which it enters, a cotter pin, or the like, 53, whereby the tube 45 cannot be moved inward or pulled out. The bottom of the float 30 normally rests upon the flat sides 50 of the extension 48, as shown. To drain the chamber 28, the dust cap 47 is removed from the upper end of extension 46 and the latter is turned downward, rotating tube 45 in the stuffing box. This brings the upper end of extension 46 below the level of the oil in the chamber 28, which accordingly flows out of tube 45. In turning tube 45, the under rounded side of extension 48 will be turned upward, so that as the oil flows out of the chamber, the float 30 cannot return to its lowermost position on the floor of chamber 28, but will be held elevated to hold contact arm 39 out of engagement with the contact 35. This feature constitutes an additional safety means, for, should a careless person 130

drain the chamber 28 in the manner described and fail to turn the extension 46 upward again, it will be impossible to place the burner in operation, because the circuit to the motor will be held broken by reason of the engagement of the underside of the extension 48, which, in effect, constitutes a cam surface, with the underside of float 30. Otherwise, as will be clear, should the 10 burner be placed in operation and if ignition did not occur, the fuel passing into the chamber 28 will not operate the float, but will continue to flow out through the tube 45.

I will now briefly describe the electrical wiring and controlling mechanism, and particularly with reference to the cutting out of the motor through the rise of the float 30. The electrical control mechanism is located 20 in a casing 54 (Figures 1 and 2) and is shown diagrammatically in Figure 5, the relative location of the parts, however, not being preserved, owing to the nature of the view. Entering the control box 54 are two main line wires or conductors 55 and 56, 25 which are connected to a transformer 57. The wire 56 also leads to the motor 1 and to a transformer 58 and thence back to the motor. A branch wire 59 connects wire 56 with a contact screw 60, mounted on an insulating board in the usual way within the control box 54. The wire 55 leads to a similar contact screw 61. From the low-voltage side of transformer 58 a wire 62 leads to a spark coil 63, from the secondary winding of which a wire 64 leads to the spark plug 23, previously referred to, the latter being grounded at 65. A second wire 66 leads from the low-voltage side of the transformer to a flexible contact member 67, 40 which is adapted to be moved by the cooling of a thermostatic bar 68 into engagement with a contact screw 69. From the low-voltage side of transformer 57, a wire 70 leads to a coil 71 surrounding the thermostatic bar 68, and thence to a contact plate 72 with 45 which the upper end of the thermostatic bar 68 is electrically connected. The other wire from the transformer, heretofore indicated by the numeral 38 in Figure 4, leads to the contact screw 37 and is thus electrically connected with the spring arm 39, and has interposed in its length a thermostatic switch 50 73. The wire 36, also previously referred to, leads from the contact screw 34 to the 55 coil 74 of an electro-magnet 75, thence to the contact screw 69. The electro-magnet 75 is adapted to actuate an armature 76 on which is mounted a mercury tube switch 77, the mercury in which is adapted to close 60 and open the contacts 78 connected by conductors 79 with the contact screws 60 and 61, previously referred to, and thus control the circuit to the motor. The armature 76 is pivotally mounted at 80 through the medium of an arm 81, which is electrically con-

nected with a spring switch member 82 mounted on the underside of the armature. Leading from the arm 81 is a wire 83 which passes to a contact screw 84 grounded at 85.

The thermostat 73 is located in the room 70 whose temperature is to be controlled, and when this temperature falls below a given degree, it moves to close the circuit over the wire 38. Thence the circuit is completed over the arm 39, contact 35 and wire 36 to 75 the electro-magnet 75. In its normal or cooled condition, the thermostatic bar 68 occupies a position to the left of that shown in Figure 5 in which the contacts 69, 67 and 68 are in engagement. Hence the magnet 80 will be energized and draw downward the armature 76 tilting the mercury in tube 77 to the right to close contact 78 whereby the circuit to the motor will be closed and the burner placed in operation. Contact between the bar 68 and the contact 67 places 85 the spark plug circuit in condition to be closed when the circuit to the motor is closed. The current passing through coil 71 heats the bar 68 in a short while and causes it 90 to move to the right or out of engagement with the flexible contact 67 thereby breaking the circuit to the spark plug and the circuit to coil 74 over the thermostatic line 38. But when the armature is attracted by the magnet, a parallel circuit is closed over the switch arm 82 and wire 83 and this parallel circuit maintains the electro-magnet energized so that the burner will continue to operate. Should the main line circuit over the wires 55 and 56 be suddenly turned off and then on, which frequently occurs in cities, no harm can result because when the current was turned off the circuit to the magnet 75 would be broken and the armature 105 76 would rise and the sudden turning on of the current cannot energize the magnet because this cannot occur until the thermostatic bar 68 has cooled sufficiently to move 110 to the left.

Assuming now that when the thermostatic circuit was closed and the motor placed in operation to supply fuel, the latter, for some reason or other, should not be ignited by the spark plug. In this case the unignited fuel, 115 as previously explained, will flow into the float chamber 28 and cause the float 30 to rise so that the stem 31 will engage the arm 39 and raise the same, thereby breaking the circuit over the wire 38 and consequently breaking the circuit to the motor. The operation of the apparatus would then instantly cease. The same result occurs when the extension 46 of tube 45 is turned downward, in which event the float 30 is mechanically raised to break the circuit over the wire 38 to the thermostat. 125

In prior constructions embodied in various applications of mine now pending, the spray nozzle 11 was located at the end of a conical 130

projection which extended, in some instances, almost into the entrance end of the flame director. In the present case, and as shown by Figure 2, the nozzle 9 projects only 5 slightly beyond the front wall of the air chamber leaving considerable space between the inner end of pipe 10 and the end of the spray nozzle, which gives opportunity for the ignited sprayed fuel to play upon the 10 converging walls 19 of the restricted inlet openings to said pipe, thus heating the same and facilitating the vaporization and combustion of the liquid fuel. In addition, the 15 space provided gives full opportunity for circulation and intimate mixture of the air admitted to chamber 5 with the fuel sprayed therein.

I claim:

1. In an oil burning system of the class described, in combination with a chamber for receiving unignited oil, a float in said chamber, and a cut-out device adapted to be actuated on the rise of said float, to stop the operation of the system, means for draining 20 said chamber comprising a tube rotatably mounted in the wall of said chamber, having an upward extension outside of the chamber and carrying a cam member projecting into the chamber and located beneath said float, 25 whereby, upon turning said extension downward to drain the chamber, said tube will be 30

rotated to cause the cam member to raise said float and thereby actuate the cut-out device or, if the float is in a raised position, will prevent its fall to normal position until 35 said extension has been raised.

2. A safety device for use in oil burning systems, comprising a chamber adapted to receive delivered oil upon failure of ignition, a float in said chamber, a cut-out controlling the operation of the system and adapted to be operated on rise of the float to stop the operation of the system, and means for draining said chamber comprising a tube 40 rotatably mounted in the wall thereof and having a substantially semi-cylindrical extension projecting under the bottom of said float with its flat edges engaging said bottom, and an upward extension located outside of the chamber, whereby, upon turning said extension downward to drain the chamber, the rounded portion of said extension will be turned upward against the bottom of the float and cause the same to rise to 45 actuate said cut-out or, if the float is in an elevated position, due to liquid in said chamber, will prevent the return of the float to normal position until said extension has been turned upward again.

In testimony whereof, I have hereunto set 50 my hand.

LEWIS L. SCOTT.
